BONNET FOR A WATER CONDITIONING TANK

Robert J. King, Brookfield, Wis., assignor to Mermaid,
Inc., Butler, Wis., a corporation of Wisconsin

Filed May 3, 1965, Ser. No. 85,071

Term of patent 14 years

(Cl. D91—1)

Fig. 1.

Fig. 2.

Fig. 3.

FIG. 1 is a side elevation of the bonnet for a water conditioning tank showing my new design;

FIG. 2 is a perspective view of the bonnet; and

FIG. 3 is a plan view.

The tank shown in broken lines in FIG. 1 is included for illustrative purposes only.

I claim:

The ornamental design for a bonnet for a water conditioning tank, as shown and described.
